Primary Examiner—James R. Largen

Attorney, Agent, or Firm—Robert N. Schlesinger

[57] **CLAIM**

The ornamental design for a water flow distributor, as shown and described.

DESCRIPTION

FIG. 1 is a bottom isometric view of a water flow manifold showing my new design;

FIG. 2 is a bottom plan view thereof;

FIG. 3 is a top isometric view thereof;

FIG. 4 is another top isometric view thereof;

FIG. 5 is a top plan view thereof; and,

FIG. 6 is a side elevational view thereof, the other sides being the same as the side shown.

FIG. 1

FIG. 2

FIG. 3

FIG. 4

FIG. 5

FIG. 6
